THREAD CONTROL SYSTEM FOR WEFT REPLENISHING LOOMS

Richard G. Turner, Worcester, Mass., assignor to Crompton & Knowles Loom Works, Worcester, Mass., a corporation of Massachusetts

Application March 8, 1943, Serial No. 478,329

18 Claims. (Cl. 139—256)

This invention relates to systems for the control of weft threads in a group of weft replenishing looms and it is the general object of the invention to provide a common pneumatic reservoir connected to the thread removers of the several looms in the group.

Heretofore I have proposed a pneumatic thread removing system for weft replenishing looms wherein an air pump operating at sub-atmospheric pressures is utilized to remove the threads of the outgoing and incoming bobbins which remain in the path of the shuttle incident to a weft replenishing operation of the loom. The pump is operated by the lay to create a partial vacuum as the lay moves from front to back center, and the pump piston moves most rapidly at top center, but this is the point in the loom cycle at which shuttle picking occurs. As a result of this timing the pump places a peak load demand on the loom at the instant when considerable power is required to drive the shuttle.

It is an important object of my present invention to connect a common reservoir to a group of pumps, one for each loom, and operate the pumps by the loom lays as the latter move from back to front center, thereby placing the demand for maximum power so far as the pump is concerned at some time in the loom cycle other than the time at which picking occurs. The sub-atmospheric pressures thus created within the reservoir are used to operate each pneumatic thread control system during the backward stroke of the associated lay at a time when the pump has an idle stroke and require very little power from the looms.

In order to prevent unnecessary loss of pressure from the reservoir during that part of the loom cycle when sub-atmospheric pressures are not needed, that is, when the lay is moving forwardly, it is a further object of my present invention to provide a valve between the common reservoir and each thread system which will close the latter as its corresponding lay advances, but will open the system as the lay recedes.

It is a further object of my present invention to provide a common reservoir constructed of units, one for each loom in a group, wherein each unit is provided with means for connection with the corresponding thread control system and also to the associated pump. The reservoir thus made can be enlarged to accommodate a varying number of looms in the group which it serves.

In the modified form of the invention the common reservoir may be supplied with sub-atmospheric pressures by means of a pump driven inde-

pendently of the looms and acting to create sub-atmospheric pressures within the reservoir whenever any of the looms in the group are running. In this modification the units of the reservoir will omit the connections for individual pumps as already mentioned, but will have connections with their corresponding thread control systems.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a diagrammatic plan view of a group of four looms showing the manner in which the preferred form of my invention operates with respect to the group;

Fig. 2 is a side elevation of one of the looms and its pump, showing connections from the latter to the common reservoir;

Fig. 3 is a diagrammatic front elevation of the thread control system of each loom;

Fig. 4 is a detail side elevation, partly in section, setting forth the valve mechanism for closing the thread control system of the associated loom during that part of its cycle corresponding to movement of its lay from back to front center;

Fig. 5 is a view similar to Fig. 4 but showing the valve mechanism in open position;

Fig. 6 is a vertical section on line 6—6, Fig. 4;

Fig. 7 is a detailed plan view of the common reservoir showing the unit construction thereof;

Fig. 8 is a detail vertical longitudinal section through one of the pumps, and

Fig. 9 is a diagrammatic view of a modified form of the invention which utilizes a pump driven independently of the looms.

Referring to Fig. 2, which shows a loom having a pump used in the preferred form of the invention, I have shown a loom having a frame 10 and a lay L driven by a crank shaft 11 attached thereto by connectors 12. A pump P secured to the frame is provided with a piston 15 the rod 16 of which is connected to the upper end of a lever 17 pivoted as at 18 to the loom frame. A connector 19 extending between the lay and the lower part of lever 17 causes backward movement of the piston 15 as the lay moves forwardly from back to front center position, hence a partial vacuum is created in the pump P to the left of the piston as viewed in Figs. 2 and 8. A tube 20 communicates with the interior of the pump in front of the piston, and an escape valve 21 permits a bypass for the air in front of the piston when the latter moves forwardly. A flap valve

22 prevents air under compression from moving forwardly in tube 20 as the piston advances.

The loom is provided with a magazine M having reserve bobbins R from which weft ends W extend as shown in Fig. 3 to the intake mouth 25 of a pneumatic thread holder connected to a thread accumulating tube or can 26 mounted in fixed position on the loom. The loom is also provided with a thread remover or extractor E having an intake mouth 28 located between the selvage S of the cloth being woven and the shuttle box B of the lay. A tube 29 leads from the can 26 to mouth 28. A thread W' extends from the selvage into the shuttle box when the shuttle is at the magazine end of the loom.

The threads W should be kept taut and above the path of the lay and whenever one of the bobbins R is transferred into the box B its weft end W will move downwardly and be held by pneumatic attraction in the holder 25 during the pick immediately following replenishment, thereby assisting threading of the shuttle. At some subsequent pick the thread of the freshly replenished shuttle will be cut at the selvage S in well-known manner and will be drawn through the tube 25 into the can 26. On the replenishing beat the thread extractor E draws that part of thread W' extending from the shuttle box to the extractor into the latter, and when this thread is later cut at the selvage the whole of the thread moves through the extractor and along a pipe 29 to the can 26. Both of these threads are thus removed pneumatically from the path of the shuttle.

Except as indicated hereinafter the matter thus far described is of usual construction and may be made as set forth in my prior Patents Nos. 2,199,353; 2,199,296 and 2,162,290. The partial vacuum within the can 26 serves to hold the weft ends W in proper position and both the thread holder and the extractor operate to remove their respective threads so that the latter will not be whipped into the warp shed by the shuttle.

In the diagram shown in Fig. 1 I have shown four looms L₁, L₂, L₃ and L₄. These looms are all substantially the same as the loom shown in Figs. 2 and 3 and each will have a lay operated pump, a bobbin magazine, a thread holder, and a thread extractor. Located at some point convenient to the looms is a pneumatic reservoir 35 formed of units 35¹, 35², 35³ and 35⁴ for the looms L₁, L₂, L₃ and L₄, respectively, and each unit will be connected to its corresponding pump by the previously described tube 20. As the looms operate they act by their pumps to create reduced pressures within the reservoir 35.

In order that the thread removing mechanisms of each loom may be connected to the reservoir 35, each can 26 is connected by a tube 40 to its corresponding unit of the reservoir 35. Thus, the can 26 of loom L₁ is connected by its tube 40 to unit 35¹, the can of loom L₂ is connected by its tube 40 to unit 35², etc.

Each lay on its forward stroke will cause the associated pump to draw air from the reservoir 35 and sufficiently low pressures will be maintained within the reservoir so that all of the cans 26 and their corresponding thread holders 25 and thread extractors E will operate satisfactorily to remove the threads already described. It is a matter of common experience that even though a group of looms are intended to run at exactly the same speed, there is nevertheless some variation, and this condition, taken with

the fact that the weaver in starting the looms up one at a time starts each loom without regard to the position of the lay of the other, leads to asynchronism in the motions of the lays. As a result, air will be drawn from the reservoir at all times by at least one pump so that a practically continuous partial vacuum always exists within the reservoir. Even if all the lays should temporarily be moving forwardly at the same time, this condition would not last very long, since the looms would soon get out of step with each other. The cans 26 will therefore be under substantially continuous conditions of partial vacuum and the thread holders and thread extractors will operate as described.

Another feature of my invention relates to the saving of the sub-atmospheric pressures within the reservoir 35 by preventing loss during that part of the cycle of each loom when the corresponding thread holder and extractor need not operate. This feature need not be used but when employed will permit the use of comparatively small pumps. Accordingly, I provide each loom with a valve in its tube 40 so that the corresponding can 26 will be momentarily and periodically disconnected from the reservoir 35 when the associated lay is moving from back to front center. The mechanism for accomplishing this result is shown in Figs. 2, 4, 5 and 6, and includes a cam 50 secured in correct angular position on the top or crank shaft 11. This cam cooperates with a plunger 52 the stem of which is surrounded by a compression spring 53 effective to urge the plunger toward the cam at all times. The stem is connected to a vane or valve 55 slideable vertically in a fitting 56 secured as at 57 to some part of the loom frame 10. The fitting is provided with tubular ends 58 located in tube 40 when this feature is used. The cam 50 is set on its shaft in such a position as to open the valve as shown in Fig. 5 when the lay is moving from front to back center and close the valve as shown in Figs. 4 and 6 when the lay is moving from back to front center. Each valve is closed in correct timed relation with respect to its loom and without regard to the positions of the other valves in the group.

The common reservoir 35 may be constructed as shown in Fig. 7. Each unit comprises a pipe 60 and the end pipes are closed by the caps 61. Threaded fittings 62 and 63 are tapped into each pipe 60 and are connected, respectively, to the tubes 20 and 40. Adjoining pipes are connected by a coupling 65. It will be apparent from Fig. 7 that I have provided a pipe 60 for each loom in the system, and that if more than four looms are used one cap 61 can be removed and other units added, one for each additional loom.

In operation, the looms in the group will all run according to their own time without regard to each other, and as each loom moves from back to front center its lever 17 will be rocked in a direction to create a partial vacuum in front of its piston 15, thereby also creating a partial vacuum in the reservoir 35. During this forward movement of the lay the valve 55 in the corresponding tube 40, if used, will be closed. On the backward stroke of the lay when the pump is not creating vacuum, the valve 55 will be open and the interior of reservoir 35 will be connected to the can 26. The thread holder and thread extractor of the loom will therefore operate on the backward stroke of the lay in a manner similar to that set forth in the previously mentioned patents. It is to be understood that

the conditions just described exist for each loom.

In the modified form of the invention I use a single air pump connected directly to the reservoir and driven by its own source of power independently of the looms. Thus, as shown in Fig. 9, a vacuum pump 75 connected to a motor 76 controlled in any approved manner by the weaver is connected by a tube 77 to a reservoir R' which is similar to the reservoir 35 already described except for a cap 78 at one end thereof which is provided with an inlet 79 for connection with the tube 77. The reservoir units 80, one for each loom, will have a single inlet 81 for attachment to the tubes 40 and the tube 20 will be omitted as well as its connection with the reservoir R'. The pump 75 runs continuously throughout loom operation to create sub-atmospheric pressures within the reservoir R' and the latter, acting through the tubes 40, will induce movement of a column of air into each of the thread controllers for purposes similar to those already described. Where the capacity of the pump 75 is sufficiently high it will not be necessary to use the valve shown in Figs. 4 and 5, but these valves can be used if desired for the purpose of permitting the use of a lower capacity vacuum pump.

From the foregoing it will be seen that I have provided a common reservoir for operating the thread control systems of a group of looms each provided with an air pump which is operated by forward motion of the associated lay. It will also be seen that each loom may be provided with a valve 55 which disconnects its pneumatic system from the reservoir while the corresponding lay is moving from back to front center and while the associated pump is operating to create a partial vacuum within the reservoir. It will also be noted that the reservoir is built up of a series of units and can be extended to accommodate additional looms. Furthermore, the reservoir need not be fed by individual pumps, one for each loom, but can be connected to a single pump operating independently of the looms.

Having thus described my invention it will be seen that changes and modifications may be made therein by those skilled in the art without departing from the spirit and scope of the invention and I do not wish to be limited to the details herein disclosed, but what I claim is:

1. In a thread control system for a group of weft replenishing looms operating at different speeds and each loom having a pneumatic thread remover to remove a thread by suction on the backward stroke of the reciprocating lay of the loom subsequent to a replenishing operation, said system comprising a reservoir common to the group of looms, means for each loom pneumatically connected to the common reservoir and operated by the corresponding lay when the latter moves forwardly to create sub-atmospheric pressures within the reservoir, and a pneumatic connection from the reservoir to each thread remover in the group.

2. In a thread control system for a group of weft replenishing looms operating at different speeds and each loom having a pneumatic thread remover to remove a thread by suction on the backward stroke of the reciprocating lay thereof subsequent to a replenishing operation, said system comprising an air pump for each loom, a common reservoir for the group of looms connected to each air pump, driving connections between each lay and the corresponding pump to cause the latter to create sub-atmospheric pres-

sures within the reservoir when the lay moves forwardly, and pneumatic connections between said reservoir and each thread remover.

3. In a thread control system for a group of weft replenishing looms having reciprocating lays which move asynchronously with respect to the times when they reach their forward positions, each loom in the group having a pneumatic thread remover to remove a thread by suction on the backward stroke of the corresponding lay subsequent to a replenishing operation, said system comprising a reservoir common to the group of looms and pneumatically connected to each of said thread removers, and means for each loom pneumatically connected to said reservoir and operated by the corresponding lay when the latter moves forwardly to create sub-atmospheric pressures within said reservoir.

4. In a thread control system for a group of weft replenishing looms having reciprocating lays which move asynchronously with respect to the times when they reach their forward positions, each loom in the group having a pneumatic thread remover to remove a thread by suction on the backward stroke of the corresponding lay subsequent to a replenishing operation, said system comprising an air pump for each loom, a pneumatic reservoir connected pneumatically to said air pumps and common to the looms of the group and pneumatically connected to each thread remover, and driving connections between each lay and the corresponding air pump to cause the latter to create sub-atmospheric pressure within said reservoir when the associated lay moves forwardly.

5. In a thread control system for a group of weft replenishing looms each of which is provided with a reserve bobbin having a weft end extending to a pneumatic thread holder to be held by the latter when the shuttle connected thereto is picked on the backward stroke of the lay subsequent to a replenishing operation, the lays reaching their forward positions asynchronously, said system comprising an air pump for each loom, a pneumatic reservoir common to the group and connected pneumatically to each air pump, driving connections between each lay and the corresponding air pump to cause the latter to create subatmospheric pressure within the reservoir when the lay is moving forwardly, and pneumatic connections between the reservoir and each thread remover.

6. In a thread control system for a group of weft replenishing looms, each loom having a thread to be removed from the shuttle path by a pneumatic thread remover during backward movement of the lay when the shuttle is picked subsequent to a replenishing operation of the loom, and the lays of the looms in the group moving asynchronously with respect to the times at which they reach their front center positions, said system comprising an air pump for each loom in the group, a pneumatic reservoir common to the group and connected pneumatically to each air pump, operating connections between each lay and the corresponding pump to cause the latter to create sub-atmospheric pressures within the reservoir when the lay moves forwardly, and pneumatic connections from said common reservoir to each thread remover in said group.

7. In a thread control system for a group of weft replenishing looms, each loom having a thread to be removed from the shuttle path by a pneumatic thread remover during backward movement of the lay thereof subsequent to a

replenishing operation, and each loom having a shuttle picking operation while the lay thereof is moving rearwardly, and the lays moving asynchronously with respect to the times at which they reach their front center positions, said system comprising a pneumatic reservoir common to the looms of said group, means for each loom pneumatically connected to the reservoir and operated by the corresponding lay when the latter moves forwardly to create sub-atmospheric pressures within said reservoir, and pneumatic connections between the reservoir and each thread remover.

8. In a thread control system for a group of weft replenishing looms having reciprocating lays which move asynchronously with respect to the times when they reach their forward positions, each loom in the group having a pneumatic thread remover to remove a thread by suction on the backward stroke of the corresponding lay subsequent to a replenishing operation, said system comprising a primary pneumatic reservoir common to said group of looms, an auxiliary reservoir for each loom pneumatically connected to said primary reservoir, pneumatic connections between each auxiliary reservoir and the corresponding thread remover, and an air pump for each loom caused by the corresponding lay when the latter moves forwardly to create a sub-atmospheric pressure within said primary reservoir.

9. In a thread control system for a group of weft replenishing looms each having a pneumatic thread remover and a reciprocating lay, said system comprising a pneumatic reservoir common to the looms of the group, means to create sub-atmospheric pressures within said reservoir, a pneumatic connection between the reservoir and each thread remover, and means controlled by each loom when the associated lay is moving forwardly to close said pneumatic connection and open said connection when the associated lay is moving rearwardly.

10. In a thread control system for a group of weft replenishing looms each having a pneumatic thread remover and a reciprocating lay, said system comprising a pneumatic reservoir common to the looms of the group, a pneumatic connection between the reservoir and each thread remover, means controlled by each loom to close the corresponding pneumatic connection when the associated lay is moving forwardly and open said pneumatic connection when the associated lay is moving rearwardly, and an air pump for each loom in the group pneumatically connected to the reservoir and operated by the associated lay when the latter moves forwardly to create sub-atmospheric pressures within said reservoir.

11. In a thread control system for a group of weft replenishing looms each having a reciprocating lay and a pneumatic thread remover which is connected to a thread extending from a shuttle subsequent to a replenishing operation, and each loom having a shuttle picking operation while the lay thereof is moving rearwardly subsequent to a replenishing operation thereof, said system comprising a pneumatic reservoir common to said group of looms and connected pneumatically to each thread remover in the group, an air pump for each loom pneumatically connected to the reservoir, means operated by each loom when the corresponding lay is moving forwardly to cause the associated pump to create sub-atmospheric pressures within said reservoir, and other means

controlled by each loom to disconnect the corresponding thread remover pneumatically from the reservoir when the corresponding lay is advancing and connect the associated thread remover pneumatically with said reservoir when the corresponding lay is receding.

12. In a thread control system for a group of weft replenishing looms each having a reciprocating lay and a pneumatic thread remover which is connected to a thread extending from a shuttle subsequent to a replenishing operation thereof, said system comprising a pneumatic reservoir common to said group of looms, an air pump for each loom operative when the corresponding lay is moving forwardly to create sub-atmospheric pressures within said reservoir, a pneumatic connection between the reservoir and each thread remover, a valve in each of said pneumatic connections, and means controlled by each loom to effect closing of the corresponding valve when the associated lay is moving forwardly and effect opening of said valve when the associated lay is moving rearwardly.

13. In a thread control system for a group of weft replenishing looms each having a pneumatic thread remover, said system including a pneumatic reservoir common to said group of looms and comprising a group of pneumatically connected hollow units, one unit for each loom, a pneumatic connection between each unit and the thread remover of the corresponding loom, and an air pump for each loom pneumatically connected to the corresponding unit to create sub-atmospheric pressures within said reservoir.

14. A pneumatic reservoir for a group of looms each having a pneumatic thread remover, said reservoir comprising a group of hollow units, one unit for each loom of the group, means to connect said units together to form said reservoir, and each unit having a pneumatic fitting for the corresponding thread remover.

15. A pneumatic reservoir for a group of looms each having a pneumatic thread remover and an air pump, said reservoir comprising a plurality of pipe units, one unit for each loom, means to connect said pipe units together and cause said units to form a pneumatically closed reservoir, and each unit having a fitting for the corresponding air pump and a second fitting for the corresponding thread remover.

16. A pneumatic reservoir for a group of looms each having a pneumatic thread remover, said reservoir comprising a plurality of aligned pipe units, means to connect adjacent ends of adjacent pipe units together, means to close the outer ends of the outer units, and a fitting on each unit for the corresponding thread remover.

17. In a thread control system for a group of weft replenishing looms each having a pneumatic thread remover with a thread receiving mouth, a pneumatic reservoir common to the looms of the group and comprising a series of connected units, one unit for each loom, a pneumatic connection between each unit and the corresponding thread remover, and means to create pneumatic pressure within said reservoir different from the atmospheric pressure at the mouths of said removers.

18. In a thread control system for a group of weft replenishing looms having reciprocating lays which move asynchronously with respect to the

times when they reach their forward positions, each loom in the group having a thread remover to move a thread out of the path of the shuttle thereof by a pneumatic force during backward movement of the corresponding lay, said system comprising a pneumatic reservoir common to the looms of said group, a pneumatic connection be-

tween each thread remover and said reservoir, and means for each loom operated by the latter when the lay thereof is moving forwardly to alter the pneumatic pressure within said reservoir relatively to the atmospheric pressure.

5 RICHARD G. TURNER.
